UNITED STATES PATENT OFFICE.

GEORGE MESTA, OF PITTSBURG, PENNSYLVANIA.

APPARATUS FOR PICKLING OR WASHING METAL.

SPECIFICATION forming part of Letters Patent No. 586,858, dated July 20, 1897.

Application filed March 12, 1896. Serial No. 582,939. (No model.)

To all whom it may concern:

Be it known that I, GEORGE MESTA, of Pittsburgh, in the county of Allegheny and State of Pennsylvania, have invented a new and useful Improvement in Metal Pickling or Washing Apparatus, of which the following is a full, clear, and exact description, reference being had to the accompanying drawings, forming part of this specification, in which—

10 Figure 1 is a side elevation of my improved apparatus shown as if in section on the line I I of Fig. 2 and viewed in the direction of the arrow *x*. Fig. 2 is an end elevation shown as if in section on the line II II of Fig. 1 and viewed in the direction of the arrow *y*. Fig. 3 is a detail view showing in front elevation one of the racks for upholding the metal plates. Fig. 4 is a sectional side elevation thereof. Figs. 5 and 6 are views of a modified construction of the racks. Fig. 7 is a top plan view of the apparatus, and Fig. 8 is a sectional detail of a spline connection I employ.

15 The purpose of my invention is to provide means for pickling and washing metal plates, pipes, &c., by agitating them in suitable baths, and it is especially adapted to the handling of long pieces which because of their inconvenient size have heretofore been hard to handle and have been treated by hand labor, an operation which is not only difficult but dangerous.

20 2, 3, and 3' are respectively the tanks for holding the baths of acid, water, and alkaline solution in which the metal to be pickled is successively washed. A greater or less number of tanks may be used, as needed. These tanks are of suitable length and depth and are set side by side, so that the metal to be treated after having been agitated in one tank can be moved to and agitated in the next tank in succession.

25 The apparatus for agitating the metal in what I believe to be the best form adapted to the practice of my invention is constructed as follows:

30 4, Fig. 1, are the elevated track-rails of a traveling crane, which are arranged at right angles to and above the tanks.

5 5 is the jib or platform of the crane, supported by wheels 6 on the rails and having,

preferably, also axles 7, connecting the wheels on the opposite sides, and pinions 8 on the axles in gear with racks 9, which extend beside the rails and serve to render uniform the travel of the wheels at each end of the axles. One of the axles may be rotated and the jib moved on its track by means of a chain and sprocket-wheel 7', as shown in Fig. 1, or otherwise. On the jib 5 is a crank-shaft 10, journaled in suitable bearings 11 and having at the end a worm-wheel 12 in gear with a worm 13 on a shaft 14, which extends parallel to the rails, the worm being fitted on the shaft with a feather-and-spline connection, so that as the jib is moved on the track the worm shall move therewith, that the worm-wheel shall be, therefore, in constant traveling connection with the shaft 14, and that by rotation of the latter the crank-shaft 10 may be rotated in any position of the jib.

15 15 are cross-heads suspended by connecting-rods from the cranks 16 of the shaft 10 between vertical guides 17 on the jib, so that if the crank-shaft be rotated these cross-heads 75 will reciprocate vertically. The cross-heads are connected by a shaft 18, carrying drums 19, from which depend chains or hangers 20, which support the racks 21, by which the metal pieces to be pickled are carried. The shaft 18 can be rotated by a shaft 22, which, by a traveling worm 23, worm-wheel 24, and gearing 25, is connected with the shaft 18. The gearing 25 has a feather-and-spline connection with the shaft 25', so that the drums 85 may be rotated during the reciprocation of the cross-heads. The shafts 14 and 22 are operatively connected by pulleys 14' and 22' and belt 30. By rotation of the shaft 18 the chains 20 may be wound upon or unwound 90 from the drums and the racks 21 raised or lowered accordingly. These racks are of novel construction. Each consists of a comb-like metal frame having parallel vertical bars connected at the top, but separated at the 95 bottom and throughout their length, and at their lower ends made of hook form or provided with lateral holes in line with each other, as shown in Fig. 4. By the word "slot" in the claims I intend to cover the bars provided with the slots, whether said slots are open at the side or entirely inclosed in the

form of holes through the bars. There is a suitable number of these racks, according to the length of the metal pieces to be treated. I show three of them in the drawings.

- 5 In using the apparatus for pickling metal plates the plates are set on edge parallel to each other in a suitable stationary rack 26, having a base 31, as shown in Fig. 2. The jib is moved on its track, so as to carry the racks 10 directly above the plates, and by rotating the shaft 18 the chains 20 are unwound, so as to lower the racks and to cause the comb-like arms thereof to fit between the several plates and the hook ends of the arms to pass below 15 the lower edges of the plates. A retaining-bar 27 is then put in the hooks of each rack, and when the racks are raised the lower edges of the plates will rest upon said bars and the plates will be supported thereby edgewise in 20 vertical position, as shown by full lines in Fig. 2. The jib is then moved on its track, so as to carry the racks into position directly above the acid-tank 2. The shaft 18 is then rotated so as to lower the racks with the plates 25 carried thereby into the liquid in the tank, and then by setting the crank-shaft 10 into motion the cross-heads are caused to reciprocate vertically and the plates are moved up and down within the liquid, thus subjecting 30 them to the desired agitation.

When the plates have been acted upon by the acid for a sufficient length of time, the racks with the plates are raised from the tank by rotating the shaft 18. The jib is then 35 moved so as to carry the racks over the water-tank 3, into which they are lowered and in which they are agitated, as above described, and then in like manner they are raised from the water-tank and carried to and agitated in 40 the third tank 4, containing the lime or other alkaline solution. After this final washing the plates, &c., may be carried by the crane to a rest-block or support 28, elevated somewhat above the floor-level, and deposited 45 thereupon, so that their lower edges will be held above the bars 27. These bars are then removed from the hooks, leaving the racks free to be lifted clear of the plates. The plates will then lie upon the support 28, as 50 shown in Fig. 2.

Where pipes or bars are to be washed or pickled, I employ racks modified as shown in Figs. 5 and 6, in which the bars of the racks are separated sufficiently to receive the pipes or bars between them, and they are upheld therein in several rows or series by retaining-bars 27', fitting in holes or hooks, as shown.

Within the scope of my claims many changes may be made in the form and construction of 60 the parts. For example, instead of a rotary shaft for agitating the racks I may use a reciprocating rod with bell-crank levers connected therewith and oscillated thereby, or other like mechanism, although the construction which I have shown has many peculiar 65 advantages and is claimed specifically herein.

Important features of the invention are the

combination of the crane with tanks set parallel to the jib thereof and mechanism on the jib for reciprocating the plates vertically, and 70 also the racks for holding the plates, which may be used with pickling apparatus of other construction and which are of advantage because of their lightness and ease of management and the ready access of liquid to the 75 plates which they afford.

By the use of the crane-jib with the plates suspended therefrom by two or more supports, the plates extending parallel to the jib and the tanks also parallel to the jib or to the position 80 which the jib occupies when over the same, I am enabled to treat long pieces with ease and safety. I am the first to make use of this construction, and I claim it broadly, whether a traveling crane or a swinging crane be employed. In prior devices the metal pieces have 85 been suspended crosswise of the jib.

My improved mechanism may be duplicated in a single apparatus, the two parts being adapted to operate reciprocally and to 90 balance each other.

I claim—

1. In metal pickling or washing apparatus, the combination with an overhead wheeled carrier arranged to move horizontally in parallel lines, of conveying mechanism thereon having means for supporting long sheets or strips at two or more points in their length, tanks located beneath the carrier in its path of travel and substantially parallel to each other, agitating apparatus mounted on the carrier, said apparatus being arranged to give the sheets or strips an agitatory motion in the tanks, and mechanism on the carrier for lowering the sheets into and raising them out of the tanks; said mechanism being independent of the agitating apparatus substantially as described.

2. The combination with an overhead traveling crane, of parallel tanks located beneath the same and in its line of travel, conveying mechanism on the crane having means for supporting long sheets or strips at two or more points in their length, agitating apparatus upon the crane arranged to give a vertical motion to the sheets while in the tank, a shaft extending longitudinally of the path of travel of the crane and having continuous actuating connections with the agitating apparatus, and means upon the crane for lowering the sheets into and raising them out of the tanks; substantially as described.

3. In metal pickling and washing apparatus, the combination with a traveling carrier, of reciprocating cross-heads thereon, means for reciprocating the cross-heads and drums carried thereby and carrying the supports for the metal; substantially as described.

4. In metal pickling or washing apparatus, the combination with a traveling carrier, of reciprocating cross-heads thereon, means for reciprocating the cross-heads, drums carried thereby and carrying the supports for the metal, and gearing for rotating the drums,

said gearing having a vertical shaft provided with a traveling connection with means for actuating it; substantially as described.

5. In metal pickling or washing apparatus, the combination with a traveling carrier, of a crank-shaft mounted thereon and having a traveling connection with its actuating means, drums carried by reciprocating cross-heads connected with the crank-shaft, said drums having supports for the metal, and means for rotating said drums to lower the metal into and raising it out of the tanks; substantially as described.

6. In metal pickling or washing apparatus, a support consisting of a comb-like rack arranged to receive the plates between its vertical bars, and a loose bar or bars extending across the rack-bars below the plates, the said rack-bars having slots to receive the retaining-bar; substantially as described.

20 In testimony whereof I have hereunto set my hand.

GEO. MESTA.
